CLAIM

The ornamental design for a slotted board with integral slot car and integral slot figures, as shown and described.

DESCRIPTION

FIG. 1 is a front elevational view of a slotted board with integral slot car and integral slot figures showing my new design;

FIG. 2 is a rear elevational view thereof;

FIG. 3 is a left side elevational view thereof;

FIG. 4 is a right side elevational view thereof;

FIG. 5 is a top plan view thereof.
The bottom of the slotted board with integral slot car and integral slot figures is plain and unadorned.

FIG. 1

FIG. 2

FIG. 3

FIG. 4

FIG. 5
